GLENN H. CURTISS, OF BUFFALO, NEW YORK.

HULL FOR FLYING-BOATS.

1,210,374.

Specification of Letters Patent. Patented Dec. 26, 1916.

Application filed October 18, 1915. Serial No. 56,603.

To all whom it may concern:

Be it known that I, GLENN H. CURTISS, a citizen of the United States, residing at Buffalo, in the county of Erie and State of New York, have invented certain new and useful Improvements in Hulls for Flying-Boats, of which the following is a specification.

My invention relates to boat hulls of that description commonly used in connection with the type of flying machines called flying boats. This type is characterized by the support of the tail controls upon and the passengers in the body of the boat hull which also carries abeam of itself an air supporting surface. However, as will appear hereinafter more clearly, my invention is applicable to hulls of hydroplanes of other types than flying boats.

The general object of my invention is to provide improvements in carrying capacity, strength and efficiency of such hulls, as well as to simplify the construction thereof. Such hulls have hydroplaning surfaces on their bottoms, and the simplification of construction is especially directed toward the improved planing action of such hulls through a very simple addition of lateral fin members which are used to provide an auxiliary hydroplaning surface. Great strength is secured by a system of bracing, and increased capacity is combined with increased planing surface, strength of bracing connection, and novel arrangement of passengers' cockpits with relation to the points of support of the aerial supporting surfaces.

In the accompanying drawings I show in detail those embodiments of my invention now best known to me. The development of other embodiments having similar basic characteristics is contemplated from time to time.

Of the drawings, Figure 1 is a side elevation of the boat hull of my invention; Fig. 2 is a plan view thereof; Fig. 3 is a front elevation thereof; Fig. 4 is a partial transverse sectional view; and Fig. 5 is a similar section of a modification.

The body proper of the hull is designated 10. This is of the general form commonly used by me for several years past, and which is commonly recognized as a type. It is essentially of streamline form having a rather blunt and bulged out head portion 55 which commences to taper rearwardly

slightly in advance of its center to a final terminus in the vertical rudder post section 11. The bottom 12 forms a V-shaped hydroplaning surface of a width equaling the beam of the boat, and is inclined from front to rear on a curve, as clearly appears in Fig. 1, the inclination being suitably downward at the bow and then continued at a gradually lessening degree of curvature rearwardly until its path is very nearly a straight line. This bottom terminates at 13 in what is commonly called a step, though in function it acts as a terminus of the planing surface only. The bottom 14 of the tail of the boat inclines upwardly from this point, and lies in a plane that makes a salient angle with the bottom 12 of the forward portion. Thus the surface 14 does not act as a hydroplaning surface in conjunction with surface 12. The bottom 14 is 75 very flat.

Attached to each side of the boat near the chine edge thereof is a rabbet strip 15. A wide plank or planing board 16, is secured longitudinally of the boat against the rabbet strip 15, and forms a projecting fin of relatively thin material and substantially uniform thickness. This planing board may in cases of great width be constructed of several longitudinally extended planks, but in any case its surface bottom is in lateral extension of the hydroplaning bottom of the boat, and bent in its length to conform to the longitudinal curve of such bottom. Extending longitudinally of its top at a point removed from the outer edge is a stringer 17. Secured to the side of the boat at a point removed from the chine and the rabbet strip 15, is a second rabbet strip 18. Between the rabbet strip 18 and the stringer 17 are arranged a plurality of laterally extending strut braces 19 which strongly brace the planing board from the side of the boat. A modified construction of this planing board is shown in Fig. 5, wherein the bottom, transverse ribs 20 of the body are extended laterally for the width of the planing board desired. The extended ends are then covered on both sides with a thin laminated surface stock 21 or the equivalent, and the spaces between the members 21 are closed by the filler strips 22. Thus the rabbet strip 15 is done away with and the danger of warping or springing reduced to a minimum, and the strength enhanced. The system of 110

lateral bracing 17, 18 and 19 is much the same.

5 A beam of the hull 10 and arranged for a center of pressure and center of gravity approximately vertically above the step 13, is a built-in wing supporting structure 23. This is made of wood and has the form of short stub wing sections. This structure is braced downwardly to the side of the boat by braces 24. Between braces 19 and braces 16 24, the side of the boat and the wing supporting structure 23, and the fin members or planing boards 16 (or 20 and 21) are trussed together in an extremely strong fashion. 15 Just in front of the wing supporting structure 23 and of a width substantially equal to the beam of the boat, is a pilot's cockpit 25, capable of accommodating a plural number of persons. In advance of this cockpit 20 and between it and the nose 26 of the boat, is a second and smaller cockpit 27 in which the passenger is accommodated.

The usual post bow braces 28, found so important in bracing the wing structure and 25 elevated motor from the bow of the boat, enter the hull at similar points between the two cockpits as indicated. These braces extend in a forwardly divergent manner from the engine bed beams supported thereby 30 above the boat hull and are suitably anchored directly within the hull. Continuing from the anchored extremities of these braces are the forwardly convergent post braces 29 which commonly intersect with the bottom 12 immediately in rear of what will prove the impact surface of the boat bow when a landing is made. The engine bed, accordingly, is braced securely to that bow portion where the impact shock is to 35 be expected, but is so braced by way of the intermediate hull connection as to result in an advantageous tying of the entire structure for unit distribution of the landing shocks.

40 45 What I claim as my invention is:

1. In a hull for flying boats, a V-shaped hydroplaning bottom, and a forwardly located longitudinally elongated fin member of substantially uniform thickness in lateral extension of the V-sides of said bottom.

50 55 2. A boat hull for flying boats having a hydroplaning bottom of substantially the same width as the beam of the boat, and relatively thin fin members in lateral extension of the hydroplaning bottom, each fin tapering forwardly in substantially streamline form.

3. A hull for flying boats having a forwardly disposed V-shaped hydroplaning 60 65 bottom, and fin members co-extensive with said bottom in the form of longitudinally laid planks of substantially no displacement, the width of which planks are in lateral extension of the V-sides of said bottom.

65 70 4. A hull for flying boats having a hydro-

planing bottom, longitudinally elongated relatively thin fin members in lateral extension of the bottom of the boat, and exposed struts bracing the fins to the side of the boat above the chines thereof.

70 75 5. A hull for flying boats having a hydroplaning bottom, a fin member in lateral extension thereof, a stringer laid longitudinally of the fin at a point removed from the side of the boat, and strut braces between the said stringer and the side of the boat.

6. A flying boat hull having a hydroplaning bottom, a fin member in lateral extension of said bottom, a rabbet strip laid longitudinally of the side of the boat at a 80 point removed from the chine, and strut braces between said rabbet strip and said fin at points removed from the chine.

7. A hull for flying boats having a hydroplaning bottom, a rabbet strip secured to the 85 side of the boat adjacent to the chine but removed slightly from the bottom surface, a plank laid beneath said strip flush with the bottom of the boat and having its surface in lateral extension thereof, together with struts 90 bracing said plank from the side of the boat.

8. A hull for flying boats including a supporting surface of a construction designed to form conjointly with the hull top a deck 95 extending laterally beyond the sides of the hull and a cock pit located immediately ahead of said supporting surface to permit of ingress and egress respectively to and from the hull interior via the cockpit to said deck.

9. A flying boat hull having a built in 100 wing supporting structure and a hydroplaning bottom, fin members in lateral extension of said bottom, and strut braces between the side of the boat and said built in supporting structure and said fins respectively.

10 105 10. A hull for flying boats having a hydroplaning bottom longitudinally curved front to rear, fin members comprising planks arranged with their under surfaces in lateral extension of the hydroplaning bottom and bent lengthwise to conform to the longitudinal curvature of said bottom.

11 110 11. A hull for flying boats having a hydroplaning bottom, laterally extending hydroplaning fin members continuing said bottom, and forwardly divergent post braces anchored to said hull and inclined in direction toward the impact portions of said bottom fin members.

12 120 12. A hull for flying boats having a hydroplaning bottom, laterally extending hydroplaning fins continuing said bottom, and forwardly convergent post braces anchored to said hull and connecting the impact portions of said bottom and fins thereto.

13. A hull for flying boats having a hydroplaning bottom, laterally extending planing surfaces continuing said bottom, post braces diverging from the impact por- 13

tions of said bottom and surfaces for anchorage in said hull, a driving motor for the boat, and post braces converging from the points of hull anchorage of first said braces 5 for support of said motor.

14. A hull for flying boats having a hydroplaning bottom, laterally extending fins continuing said bottom, wings built into said hull and extending there across, and individual means bracing said bottom, said fins and said extended wings directly to the sides of said hull.

15. A hull for flying boats including a built-in wing structure having its top-side 15 merging uninterruptedly into the hull deck to form therewith a relatively large deck area.

16. A hull for flying boats including a supporting surface of a construction designed to form conjointly with the hull top 20 a deck extending laterally beyond the sides of the hull, and a means bracing the extended deck area from beneath.

17. A hull for flying boats having a hydroplaning bottom of V form throughout, and relatively elongated transversely thin 25 fin-boards of substantially no displacement

in lateral extension of the V sides of said bottom.

18. A hull for flying boats having a hydroplaning bottom of V form in transverse section, and relatively narrow elongated fin members of substantially no displacement and of uniform thickness in lateral extension of the V sides of said bottom. 35

19. A hull for flying boats having a hydroplaning bottom longitudinally curved from front to rear, and fin members comprising planks arranged with their under surfaces in lateral extension of said hydroplaning bottom, each plank having a longitudinal curve substantially analogous to the curvature of said bottom. 40

20. A hull for flying boats having a hydroplaning bottom, and fin members comprising planks bent longitudinally to conform to the chine curvature of the hull. 45

21. A flying boat hull having a hydroplaning bottom, a fin member in lateral extension of said bottom, and exposed means 50 bracing the fin member at intervals throughout its length to the sides of the hull.

In testimony whereof I affix my signature.
GLENN H. CURTISS.
